UNITED STATES PATENT OFFICE

2,512,753

MECHANISM FOR CLAMPING AND OPERATING ON WORKPIECES

Laurence E. Topham, Wenham, Mass., assignor to United Shoe Machinery Corporation, Flemington, N. J., a corporation of New Jersey

Original application March 10, 1945, Serial No. 582,011. Divided and this application November 14, 1946, Serial No. 709,831

4 Claims. (Cl. 144—93)

1

This invention relates to an improved mechanism for clamping and operating on work parts and is herein illustrated as applied to a last drilling machine of the type disclosed in an application for Letters Patent of the United States, Serial No. 582,011, filed on March 10, 1945, of which this application is a division. It will be understood, however, that this invention is not limited to machines of that particular type but is broadly applicable in any machine having a power driven tool for performing an operation on a work piece, a support for the work piece adapted to present the work piece to the tool and mechanism for moving the tool into and out of engagement with the work piece.

It is the purpose of the invention to provide a simple yet effective mechanism insuring that the work piece will be firmly clamped upon the support and that the tool cannot be moved into operative engagement with the work piece unless and until the latter is firmly clamped in operative position on the support.

To this end and in accordance with the invention, there is provided a work clamping member which is moved into clamping engagement with the work piece on the support by operator controlled mechanism. This operator controlled mechanism includes connections to mechanism for moving the tool into engagement with the work piece, and these connections are so constructed and arranged that on operation of the operator controlled mechanism the clamping member is first moved into clamping engagement with the work piece and then automatically locked in work clamping position, whereupon continued operation of the operator controlled mechanism causes movement of the tool into operative engagement with the work.

These and other features of the invention will now be described in detail in connection with the accompanying drawings and will be pointed out in the appended claims.

In the drawings,

Fig. 1 is a view, substantially in front elevation, of a last drilling machine in which the invention is shown as embodied;

Fig. 2 is a detail view, in front elevation, of a holdown mechanism and drill elevating mechanism associated therewith;

Fig. 3 is a plan view of the parts substantially as shown in Fig. 2; and

Fig. 4 is a detail view partly broken away and in cross section, taken along the line IV—IV of Fig. 3, viewed in the direction of the arrows.

The illustrated last drilling machine serves to bore a thimble hole into the top face or crown

2

of the heel and of a shoe last L resting bottom up on a last support P with which the machine is provided.

The frame of the illustrated machine comprises a base 10 (Fig. 1) to which is secured an upright column 12. For supporting the drill head of the machine there is provided a bracket 14 (Figs. 1, 2 and 3). The bracket 14 is clamped to the column 12 by bolts 16 and extends radially therefrom. For carrying the last support a bracket 18 is provided which is also secured to the column 12 and extends radially therefrom at an acute angle to the bracket 14. Both brackets 14 and 18 are secured together by vertical screw 15 bolts 20.

The operating mechanism of the illustrated machine comprises an upwardly extending, vertically movable rotary drill 22 (Figs. 1 and 2) which is secured in a chuck 24 provided on the upper end of a rotary drill shaft 26. The shaft 26 has an enlarged portion 28 which is rotatably mounted and axially slidable in a bearing provided in the bracket 14. The lower end of the shaft 26 carries a bank of stepped pulleys 30 of different diameters and, hence, different peripheral speeds. The pulleys are splined on the shaft 26, the arrangement being so that the pulleys 30 are constrained to rotate with the shaft 26 but the shaft can move in the direction of the axis of rotation with relation to the pulleys 30, this to feed the drill 22 into the work. The pulleys 30 are driven by a belt 32 connecting a selected one of the pulleys 30 with a selected pulley of a similar but inverted bank of stepped pulleys 34 secured on the rotor shaft of a motor 36. The motor 36 is fastened to an extension 38 of the bracket 14. The entire driving mechanism is shrouded by a housing 40. The drill 22 rotates continuously so long as the motor 36 is kept running.

To operate the drill so as to cause it to bore a thimble hole into a last presented to the machine, the drill shaft 26 is elevated as a result of the depression of a treadle 42 (Fig. 1), as will be described.

The treadle in being depressed performs or initiates other operations such as causing certain mechanism to hold the last against the thrust of the drill, as will be pointed out in detail. The treadle 42 is pivotally secured at 44 to a small bracket 46 fastened to the column 12.

The illustrated machine is provided with a holdown mechanism which serves to support the last mounted on the last support P against the thrust of the drill 22 during the drilling operation. Referring to the drawings, it will be noted

that there is provided a holddown 50 which is part of a two-armed lever 52 pivotally movable about a fulcrum stud 54. The stud 54 is a floating stud and is carried by the forward end of a two-armed lever 56 which is pivoted on a screw stud 58 secured in a split sleeve 60 clamped about the column 12 by bolts 62. In its inoperative position the holddown member 50 is held elevated by means to be described. To elevate the stud 54 a spring 64 is provided which connects a projection 66 provided on the sleeve 60 with a pin secured in a socket 68 provided on the lever 52. The spring 64, in pulling up on the lever 52, elevates the fulcrum stud 54 by rocking the lever 56 about its pivot screw 58 until the rear end of the lever 56 strikes a projection 70 provided on the sleeve 60.

To move the holddown 50 into contact with the heel seat portion of the last L supported in the machine, there is provided a rod 72 which is pivotally secured by a stud 74 to the arm of the lever 52 on which the holddown 50 is provided. Upon downward movement of the rod 72, the lever 52 is rotated in a counterclockwise direction, as viewed in Fig. 2, about the stud 54. At the same time, the lever 56 is rotated in a counterclockwise direction and its rear arm is moved out of contact with the abutment 70. To move the rod 72 downward, it is provided at its lower end with a fork 76 which is pivotally connected by a stud 78 to a lever 80 pivotally movable at one end about a stud 82. The other end of the lever 80 is pivotally connected to a treadle rod 84 which at its lower end is pivotally connected to the above described treadle 42. A spring 86 connecting the treadle 42 with a bracket 88 secured to the column 12 serves to elevate the treadle into its normal inoperative position, thereby elevating the holddown.

To lock the holddown 50 in last contacting position, a pawl 90 is provided which is movable about a fixed stud 92 and which is arranged to be moved beneath the right hand arm of the lever 52 (as viewed in Figs. 1 and 2) after the holddown 50 has been moved into contact with the last. For the purpose of controlling the movement of the pawl 90 it is provided with a substantially horizontal arm which is secured by means of a screw 94 to one arm of a two-armed lever 96 which is also pivoted on the fixed stud 92. The pawl 90 is adjustable with relation to the lever 96 and to this end the horizontal arm of the pawl is provided with a vertically extending slot 98 receiving the screw 94. The screw 94 when tightened secures the pawl to the lever 96 in the selected position of adjustment. The right hand arm of the lever 96 is connected by a spring 100 with the above mentioned abutment 70 on the sleeve 60. The spring 100 tends, after the holddown has been moved into contact with a last mounted on the last support P, to swing the lever 96 in a counterclockwise direction, as viewed in Fig. 2, to move the pawl 90 beneath the right hand arm of the lever 52 and to prevent clockwise rotation of the lever 52 as a result of which the holddown would be raised from the last. In the inoperative position of the parts (Fig. 2), the left hand extremity of the lever 96, which is fork shaped and rests on the flat top face of the fork shaped end 76 of the rod 72, is prevented from moving down so as to swing the pawl 90 into locking position because the rod 72 and the fork shaped end 76 are in their elevated positions. However, after downward movement of the rod 72 and counterclockwise movement of the lever 75

52 to move the holddown 50 into contact with the last, both the lever 96 and the pawl 90 are now free to be rotated in a counterclockwise direction about the stud 92 by the spring 100, thus locking the lever 52 and the holddown 50 in operative positions.

The above described mechanism for moving the holddown 50 into last engaging position and for holding it in that position is connected with mechanism for elevating the rotary drill 22 so as to feed it into the work. It should be noted that the above mentioned pivot stud 82 is only stationary so long as the lever 52 is rotated in a counterclockwise direction to move the holddown into last engagement. After the holddown is in engagement with the last and the lever 52 has been locked by the pawl 90 so that it can rotate neither in one direction nor the other, the rod 72 no longer can be moved downward and, consequently, the pivot stud 78 now becomes a fixed fulcrum about which the lever 80 is rocked in a counterclockwise direction upon continued movement of the treadle rod 84. The result is an elevation of the pivot stud 82. The latter is connected by a rod 102, which is adjustable in length, to an arm 104 which is secured on a rockshaft 106. The shaft 106 is mounted in suitable bearings in the bracket 14 and carries a splined gear segment 108 which meshes with a pinion 110 (Figs. 3 and 4) formed on a countershaft 112 rotatable in bearings in the bracket 14. The pinion 110 meshes with a rack 114 provided on the portion 28 of the shaft 26. Consequently, on elevation of the pivot stud 82 after the holddown 50 has been moved into last engagement and locked, the arm 104, as a result of the continued downward movement of the treadle rod 84, is rotated to elevate the drill shaft 26 through the agency of the gear segment 108, pinion 110 and rack 114. The advantage of this mechanism is that both the locking of the last L against the thrust of the drill 22 and the feeding of the drill are effected by one continuous treadle operation and that the drill cannot be fed into the last until after the last has been engaged by the holddown and the holddown has been locked in last engaging position.

In the operation of the machine a last L to be drilled is mounted on the last support P. Thereafter the treadle 42 is depressed with the result that the holddown 50 is brought down into engagement with the heel seat portion of the supported last and is locked in last engaging position as described.

By the continued depression of the treadle the drill 22, which is continuously rotated, is elevated to engage the top face of the heel end of the last and is fed into it so as to bore a thimble hole into the last. This having been accomplished, the treadle 42 is released and is pulled up by the spring 86 with the result that the drill is lowered. After the drill has been lowered into its inoperative position, continued upward movement of the treadle 42 causes the positive unlocking of the lever 52 by the engagement of the upwardly moving fork 76 with the latch controlling lever 96. Finally, the holddown 50 is swung upward and its floating fulcrum stud 54 is elevated by the spring 64 until the arm of the lever 56 again engages the abutment 70.

Having described my invention, what I claim as new and desire to secure by Letters Patent of the United States is:

1. In a machine for operating on a work piece, a support for the work piece, a tool movable with

relation to the support to operate on the work piece, means for so moving the tool, a clamp adapted to engage the work piece on the support to hold the work piece against the thrust of the tool, means for moving the clamp into engagement with the work piece, a latch for locking the clamp in work-engaging position, a connection between the clamp-moving means and the latch for rendering the latch operative on movement of the clamp into work-engaging position, a connection between the clamp-moving means and the tool-moving means, and means active after the clamp has been locked to render the last-mentioned connection effective to move the tool with relation to the support.

2. In a machine for operating on a work piece, a support for the work piece, a tool movable with relation to the support to operate on the work piece, a clamp for holding the work piece on the support against the thrust of the tool, clamp-operating means, tool-operating means, an operating lever, a connection between the lever and the clamp-operating means, another connection between the lever and the tool-operating means, and an operator-controlled means for rotating the lever about the last-mentioned connection to operate the clamp and then for rotating the lever about the first-mentioned connection to operate the tool.

3. In a machine for operating on a work piece, a support for the work piece, a tool movable with relation to the support to operate on the work piece, a clamp for holding the work piece on the support against the thrust of the tool, clamp-operating means, tool-operating means, a latch for locking the clamp in work-clamping position, a spring tending to move the latch into locking position, a link connecting the latch with the clamp-operating means and normally holding the latch out of its locking position, an operating lever, a connection between the lever and the

clamp-operating means, another connection between the lever and the tool-operating means, and operator-controlled means for rotating the lever about the last-mentioned connection to operate the clamp and permit the spring to move the latch into its locking position and for then rotating the lever about its first-mentioned connection to operate the tool.

4. In a machine for drilling the heel ends of lasts, an upwardly extending and upwardly movable drill, a last support for presenting a last to the drill in a position for the drill to bore a thimble hole into the top face of the heel end of the last, a holddown for holding the last on the support against the upward thrust of the drill, means for moving the holddown into engagement with the last prior to the initiation of the last-drilling operation, means for moving the drill upwardly, a latch for locking the holddown in last-engaging position, a connection between the holddown-moving means and the latch for rendering the latch operative on movement of the holddown into work-engaging position, a connection between the holddown-moving means and the drill-moving means, and means active after the holddown has been locked to render the last-mentioned connection effective to move the drill upwardly.

LAURENCE E. TOPHAM.
